DESIGN FOR A MOCCASIN OR SIMILAR ARTICLE

Edward J. Biel, Brookline, Mass.

Application August 20, 1938, Serial No. 79,480

Term of patent 3½ years

To all whom it may concern:

Be it known that I, Edward J. Biel, a citizen of the United States of America and resident of the city of Brookline, county of Norfolk, State of Massachusetts, have invented a new, original, and ornamental Design for a Moccasin or Similar Article, of which the following is a specification, reference being had to the accompanying drawing, forming a part thereof.

In the drawing:

Figure 1 is a top plan of a moccasin or similar article, showing my new design; and
Fig. 2 is a side elevational view thereof.

I claim:

The ornamental design for a moccasin or similar article, substantially as shown.

EDWARD J. BIEL.
